SANDING MACHINE

Frans O. Albertson, Sioux City, Iowa, assignor to
 Albertson & Company, Inc., Sioux City, Iowa,
 a corporation of Iowa

Application January 19, 1935, Serial No. 2,458

4 Claims. (Cl. 172—36)

The present invention relates to sanding machines, and particularly to improved methods and apparatus for the ventilation of sanding machine motors.

In the sanding machines of the prior art, the moving parts of the motor, especially the commutator, have been subjected to severe wear and destruction on account of the presence of the abrasive particles resulting from the sanding operation. These abrasive particles include not only the substance which is ground off the automobile body, but the particles of emery and carborundum which form a part of the abrasive on the sanding wheel and which are worn off. These abrasive particles are sucked in at the intake end of the ventilation system of the motor and come into direct contact with the commutator, causing such severe wear that the commutator often has but a small portion of the useful life which it should have in a commercially successful machine.

The motor structure is, of course, capable of general application and may be used upon electrical drills or driving motors of any kind where it is desirable to protect a commutator and/or to provide special means for its cooling.

One of the objects of the invention is the provision of an improved ventilation system or method of ventilation and an improved apparatus by means of which the abrasive particles in the adjacent atmosphere are prevented from coming into contact with the commutator of the sanding machine motor.

Another object of the invention is the provision of an improved method and apparatus of the class described in which provision is also made for the removal of the heat from the vicinity of the commutator.

Another object of the invention is the provision of an improved motor structure for sanding machine motors in which the motor is provided with an improved baffle arrangement capable of preventing abrasive particles from reaching the commutator and also capable of effecting the removal of the heat from the vicinity of the commutator.

Another object is the provision of an improved and simplified structure which may be readily applied or adapted to the existing motor structures and which may be manufactured at a very low cost.

Another object is the provision of an improved ventilation arrangement which requires no attention, replacement or cleaning, such as would be required if air, straining or cleaning elements

were used at the air intake to the ventilation system of the motor.

Other objects and advantages of the invention will be apparent from the following description and the accompanying drawing, in which similar characters of reference indicate similar parts throughout the several views.

Referring to the single sheet of drawing, Fig. 1 is a view in perspective of a sanding machine of the type constructed according to the present invention;

Fig. 2 is a longitudinal sectional view taken on the plane of the axis of the motor shaft, with the armature in elevation and the other fragments of the motor in section, showing the details of construction of the present invention in section;

Fig. 3 is a transverse sectional view of the motor of Fig. 2, with the armature removed and with the housing in section on the plane of the line 3—3 of Fig. 2, showing the baffle which directs the air coming in the intake in such manner as to prevent the grit from reaching the commutator;

Fig. 4 is a view in perspective of the baffle utilized in the present invention; and

Fig. 5 is a sectional view of the baffle alone as it would appear if taken on the line 5—5 of Fig. 3.

Referring to Fig. 1, the sanding machine in question preferably includes an electric motor 10 provided with a gear housing 11 having the laterally projecting drive shaft 12 which carries the sanding wheel 13. The gear housing is provided with a handle 14, and the motor is also provided with an axially extending handle 15 having a ball formation 16 for engagement in the palm of the hand. The rectangular or box-like formation 17 on the motor is a switch housing including the motor control switch 18 for starting and stopping the electric motor.

The sanding wheel 13 includes a suitable metallic base 19 and a resilient flexible metallic disc 20 which supports a rubber disc 21. The rubber disc is covered on its forward face with a sheet of emery paper or other suitable flexible abrasive 22. The motor 10 is provided with suitable ventilation openings 23 comprising the outlet openings and the inlet ventilation openings 24 at the opposite end.

The purpose of the present invention is the protection of the moving parts of the motor from the grit or abrasive coming from the rotating sanding disc 22 and drawn in through the openings 24 at the top and bottom of the motor housing adjacent the switch housing 25.

Referring now to Fig. 2, the motor housing preferably comprises a substantially cylindrical member 26 which is provided with an inwardly curved end portion 27 terminating in a substantially rectangular end 28 to be joined to the switch housing 25.

The curved end portion 27 of the motor housing is provided with the longitudinally extending slots 24 previously identified as intake ventilation openings. At the opposite end of the motor it is provided with an annular metal member 29 having slots 30 cut away and leaving the projecting cylindrical portions 31 for engagement with the wall of the motor housing 26 and for passage of the securing screw bolts 32. The slots 20 cooperate with the motor housing 26 in forming the outlet ventilation apertures previously identified with the numeral 23 and surrounding the periphery at the motor at the left end of Fig. 2.

The motor may be provided with any suitable type of bearings and with a shaft 33 supporting armature 34. Shaft 33 supports a fan 35 having blades 36 extending radially and longitudinally from the body of the fan 25. The commutator 37 is located at the opposite end of the motor shaft 33 and ordinarily is directly in line with the path of the incoming air taken in at the apertures or slots 24.

The motors constructed according to the present invention are preferably provided with an inwardly extending cylindrical boss 38 surrounding the anti-friction bearing 39 which supports the right end of the shaft 33 in Fig. 2.

The cylindrical boss 38 may be utilized for supporting a baffle 40 (Fig. 4) by providing the baffle 40 with an inwardly extending cylindrical formation 41 having a close frictional fit with the exterior of the boss 38. The baffle is also provided with a pressed formation 42 for accommodating a boss formed on the interior of the motor housing for the purpose of housing a lubrication conduit, but in other embodiments of the invention the formation 42 may be wholly omitted.

Baffle 40 extends about the tubular or cylindrical formation 41 and curves outward and backward in the same direction as the tubular formation 41, being provided with two main body portions 43, 44. It is also provided with laterally projecting attaching flanges 50 having apertures 51 for reception of the screw bolts 52 which are threaded into the body of the motor and which secure the baffle against rotation on the boss 38.

Body portions 43, 44 are suitably curved so that they are spaced from the interior of the motor housing 26, thereby leaving the ventilation space 27. The portions 43, 44 of the baffle preferably extend into the motor housing far enough so as to overlap the motor field 45 and control the flow of all of the ventilating air passing in at this end of the motor housing.

At a point which is preferably just beyond the end of the slots 24, each of the portions 43, 44 is provided with a slot 46, 47 formed by slitting the metal and pressing the material at one side of the slot upward and the other side downward. This forms a slot which extends in the direction of the plates 43, 44, and the slots are preferably so arranged that they open in toward the commutator.

The size of the slots 46, 47 is preferably smaller than the cross section of the adjacent ventilation conduit so that the slots 46, 47 represent

only a small portion of the cross section of the ventilation conduit at the intake end.

It will be observed that the slots 46, 47 are located just beyond the intake slots 24 and at a restriction in the intake line of the ventilation system. The arrangement is such, therefore, that the slots 46, 47 act like openings located at the restriction of a Venturi tube, and it is found that air is drawn in the direction of the arrows in Fig. 2 from the commutator 37.

The baffle 40 being arranged about the commutator in front of the ventilation slots 24, as shown in Fig. 3, it prevents the gritty air from coming into direct contact with the commutator and causes the air to pass on through the ventilation openings 48 which surround the field core 45. The heat generated through the friction and sparking at the commutator is dissipated by drawing the air out of the space surrounding the commutator through the Venturi tube slots 46, 47, and air is drawn into the space surrounding the commutator by natural ventilation; that is, through any other holes, apertures or cracks which lead to this space 49.

Many other methods of ventilation were tried before this method and apparatus were discovered, but none were so effective as the present structure including the baffle and Venturi slots. By means of this arrangement the commutator is kept reasonably cool and the other parts of the motor are suitably cooled, but the gritty ventilating air is prevented from coming in direct contact with the armature, and its destructive action on the armature is eliminated or at least so greatly reduced as to eliminate armature trouble.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. In an electric motor, a motor housing provided with air intake and air outlet ventilation apertures, a motor in said housing provided with a fan, said motor having a commutator arranged adjacent the air intake openings and a baffle arranged about said commutator to form a ventilation conduit between said baffle and housing to deflect from said commutator the air coming in said intake apertures, said conduit having a restriction to increase air velocity at that point and said baffle being provided with a ventilating aperture arranged near the restriction in the ventilation conduit between said baffle and the motor housing whereby air is drawn from the space surrounding said commutator to discharge the heat from said commutator.

2. In an electric motor, a motor housing provided with air intake and air outlet ventilation apertures, a motor in said housing provided with a fan, said motor having a commutator arranged adjacent the air intake openings and a baffle arranged about said commutator to form a ventilation conduit between said baffle and housing to deflect from said commutator the air coming in said intake apertures, said conduit having a restriction to increase air velocity at that point and said baffle being provided with a ventilating aperture arranged near the restriction in the ventilation conduit between said baffle and the motor housing whereby air is drawn from the space surrounding said commutator to discharge the heat from said commutator.

space surrounding said commutator to discharge the heat from said commutator, said motor housing having a boss surrounding its drive shaft, and said baffle having a tubular formation fitting 5 on said boss to secure the baffle in place.

3. In an electric motor, the combination of a housing provided with ventilation apertures at each end, a motor field core spaced from said housing to provide a ventilation conduit between 10 said core and housing, a motor armature carried by a motor shaft having a fan and commutator, and a baffle carried by said motor housing in between said armature and certain of said ventilation openings to direct the air from said openings into said ventilation space between said core and said housing, said baffle substantially closing the space between the end of the ventilation conduit between said core and housing and the intake apertures, said baffle having a ventilation 15 opening located at a restriction in said conduit to draw heated air from the vicinity of said commutator.

4. In an electric motor, the combination of a motor housing provided with ventilation apertures 20

5 at each end, an electric motor in said housing comprising a field core spaced from said housing at certain points to permit ventilation around said core, and comprising an armature and commutator, a fan driven by said armature for expelling air from the ventilation apertures at one end of said housing and drawing air inward through the ventilation apertures at the other end of the housing, a baffle arranged between the commutator and ventilation apertures 10 at said other end of the housing, said baffle forming a ventilation conduit with said housing and approaching said housing to form a restriction and said baffle having an aperture located adjacent said restriction to effect Venturi action 15 whereby air is drawn through said aperture in said baffle as a result of the stream of air flowing over said baffle from the intake ventilation apertures of said housing to the outlet ventilation apertures, in order to effect a cooling of the 20 armature and avoid the abrasive action of abrasive particles in the air on said armature.

FRANS O. ALBERTSON.
